UNITED STATES PATENT OFFICE.

HAZOR JUDSON SMITH, OF SPRINGFIELD, MASSACHUSETTS.

METHOD FOR PREVENTING THE FORMATION OF FROST CRYSTALS IN THE CIRCULATING LINES OF REFRIGERATING MACHINES.

Application filed June 8, 1922. Serial No. 566,820.

To all whom it may concern:

Be it known that HAZOR JUDSON SMITH, a citizen of the United States, residing at Springfield, in the county of Hampden and 5 State of Massachusetts, has invented certain new and useful Improvements in Methods for Preventing the Formation of Frost Crystals in the Circulating Lines of Refrigerating Machines, of which the following is 10 a specification, reference being made to the accompanying drawing, forming a part thereof.

This invention relates to refrigerating cycles in a refrigeration machine more particularly to the private dwelling type, in which ethyl chloride, methyl chloride or liquid refrigerant of similar properties are used. In machines of this character using the refrigerants enumerated serious operating difficulties have been encountered due to 15 the formation of frost crystals prevailing through the circulating lines of the low side of the apparatus. These frost crystals are formed from water in the system which may 20 come from condensation in the lines, moisture in the oiling and sealing medium and moisture in the refrigerating agent itself.

In the use of ethyl chloride, methyl chloride or similar agents, it has been found that these frost crystals will accumulate more particularly at the expansion valve, but also at any point in the circulating lines, such as at the bend or elbow or some low spot in the lines. At such points the frost crystals become solidly massed and shut off the circulation of the refrigerant, thereby causing the machine to cease functioning, so far as refrigerating is concerned. It becomes necessary under such circumstances to stop the machine and allow this frozen water to thaw, then the machine can again be started and refrigeration will continue. It is found, however, that the desired and particularly 45 low temperatures cannot be obtained because this freezing-up condition is accumulated from any point below 32 degrees Fahrenheit in the low or expansion side.

The objects of this invention is to provide 50 a liquid refrigerant and circulate it in the lines in such a manner that this difficulty is entirely overcome and the formation of these frost crystals is prevented within the working temperature of the machine.

The reason that ethyl chloride has not 55 been used successfully before seems to be because of the operative difficulties of keeping the gas dry or free from water and has proved a very decisive factor in driving experimenters to the other agents, such as sulphur dioxide. In machines pulling a high operative vacuum, any water in the lines will freeze at the primary expansion point and clog the lines. The harder the machine pulls the harder the freeze-up. There are 60 two reasons for this—one, the evaporation of the ethyl chloride and the other, the evaporation under high vacuum of part of the water itself. Sublimation from the surface of the frozen water constantly furnishes 70 small amounts of water to the high side which flows into the liquid receiver along with the liquefied gas. This fundamental factor of sublimation prevents fixing the water in any one spot by freezing for it will 75 ultimately land at the expansion valve in spite of all precautions.

I have found a cure for this freezing which consists in putting an alcoholic sludge in the lines that is sufficient in quantity to prevent 80 freezing, even at the lowest temperature, of any amount of water that could possibly be in the lines. I find that denatured alcohol is very good. The alcohol constantly travels through the lines of the low side and mixes 85 with the water therein. This mixture of water and alcohol can pass the expansion valve without having any effect upon the valves or lines. Three or four ounces is sufficient for the largest domestic unit. 90

I have discovered that by the addition of alcohol to the circulating lines of a refrigerating apparatus in which ethyl chloride, methyl chloride or similar refrigerants are employed, the alcohol would dissolve or deliquesce the frost crystals as rapidly as they form, and that the alcohol and moisture, or water, would together form a non-freezing sludge, which can slowly travel through the low side to some pocket without obstructing 95 the line, which can also freely pass through the expansion valve without obstructing it; I have further discovered that the tendency of this sludge is to rest quiescent in some low point in the circulating lines, such as 100 in the low point of a loop in the circulating coils or in the low side of a hollow cylinder or drum.

5 Due to the fact that the refrigerants ethyl chloride, methyl chloride or similar agents are so much more volatile than alcohol, and that they will boil at a much lower temperature, these refrigerants will circulate freely in the lines, boil off their gas, and leave behind a more sluggishly moving mass of alcohol and water. The addition 10 of alcohol to the refrigerant in the circulating system of a refrigerating apparatus successfully isolates all traces of moisture or water, permits the free circulation of the refrigerating agent, and therefore, successful functioning of the machine under 15 all conditions of practical operation, and enables the refrigerant to produce any desired temperature of which the refrigerant is capable.

20 The foregoing and other features of my invention will now be disclosed in connection with the accompanying drawing forming part of this specification, in which I have represented a refrigeration cycle in which my refrigerant may be used but I 25 do not wish to confine myself to that apparatus, nor to the particular cycle illustrated.

Having thus set forth my invention I 30 will now describe the method employed.

35 In the drawing Fig. 1 is a diagrammatic view, partly in section of a refrigerating apparatus illustrating my invention and Fig. 2 shows a variation of the expander.

40 In the drawings I have represented a diagrammatic refrigerating cycle in which the compressor or pump 1 pumps the hot gas through the tube 2, to the condenser 3, where the gas is condensed and becomes a liquid, from there it passes in liquid state through the tube 4, expansion valve 5, tube 6 to the expander 7. There the liquid boils off and becomes cold gas at low pressure, from which it is pumped through tube 8, 45 check valve 9, tube 10 through the compressor to repeat the cycle.

50 The compressor may be any well known type but I have shown a multistage pump with two pairs of helical gears 20 and 21 of different volumetric capacity decreasing from low to high. (Shown in section.) 55 is an oil separator in which the sealing oil is separated from the hot gas at high pressure dropping back into an oil receptacle. The pipe 23 connects the high side to the oiling lantern on drive shaft.

60 The condenser may be any type for the purpose of explanation, I illustrate an air cooled condenser consisting of a plurality of vertical risers ending in drums 31 and 32.

65 As these devices as well as the check valve and expansion valve are well known in the art no further detailed explanation is required.

70 In such a cycle the refrigerant after pass-

ing the expansion valve 5 in liquid form, begins to take on heat and boil and evaporates throwing off its gas. This gas is pumped out of the expander 7 by the compressor and the evaporation is very rapid, due to the amount of heat being received at the tension.

75 When I charge the condenser 3 with alcohol, the alcohol passes along with the refrigerant and sludges the low side. Any moisture in the refrigerant is left in solution with the alcohol, the refrigerant boils off leaving the water. The law of fractional distillation governs the deposit of 80 alcohol and water as the refrigerant boils off.

85 Where I charge the low side with alcohol, provision is made for a sludge pocket immediately following the expansion valve, where the alcohol may lie and entrap any frost crystals carried along by the refrigerant. These crystals are deliquesced by the alcohol and non-freezing sludge formed. This sludge being heavier than the refrigerant will rest in all the low spots in 90 the low side, provision being made that there shall be low spots in the lines.

95 Ethyl alcohol is highly miscible with water and forms with it a mixture that only solidifies at very low temperatures but the vapor tension of ethyl alcohol is about two hundred times less than the vapor tension of water, with these facts it is evident that ethyl chloride and alcohol mixed in proper proportion will produce an ideal 100 refrigerant for an automatically controlled machine without recourse to special valves or fittings for trapping out the moisture and without manual attention from time to 105 time.

110 I am aware of the fact that various mechanical means have been employed from time to time to trap out the moisture from the circulating lines and to gather the frost crystals such as manual operated valves and catch basins to pocket them off from the circulating lines and especially the expansion valve so as to permit continued flow of the refrigerant but I know of no method 115 for preventing the formation of frost crystals by the formation of an alcoholic sludge and depositing it in the low spots of the system.

120 I am further aware that alcoholic vapor has been mixed with air, in a low temperature device, in the art of desiccation of air, the mixture being condensed and trapped out of the system but I do not know of any one using a mixture of alcohol and a liquid refrigerant for the purpose of forming a 125 sludge which is pumped through the lines of a refrigerating machine to clear all frost crystals out of the lines and collecting the crystals and sludge in low spots of the 130 low side.

Having thus fully described my invention what I claim and desire to secure by Letters Patent is:

1. A method of preventing the formation of frost crystals in the circulating lines of a refrigerating machine which includes the step of mixing with the refrigerant a liquid highly miscible with water, providing a non-freezing sludge in the low side, 5 circulating the sludge through the lines and collecting it in low spots thereby preventing interference in the circulating lines.
2. A method of preventing the formation of frost crystals in the circulating lines of a refrigerating machine, which includes the step of forming an alcoholic sludge in the refrigerant, and pumping the sludge through the circulating lines and collecting it in the low side. 15
3. A method of preventing the formation of frost crystals in the circulating lines of a refrigerating machine, which includes the step of mixing with the refrigerant a less

volatile liquid than the refrigerant and one that is highly miscible with water, so 25 that the refrigerant will circulate freely, boil off its gas and leave behind an unfrozen sludge, and pumping the sludge through the circulating lines.

4. A method of preventing the freeze up 30 of the circulating lines of a refrigerating machine which includes the step of combining with the liquid refrigerant a less volatile liquid miscible with water so that a non-freezing sludge is formed within the 35 circulating lines by combining with the water found therein, and pumping the sludge through the lines to clear it of any frost obstruction and collecting the sludge in low spots in the lines. 40

In testimony whereof I affix my signature in the presence of two witnesses.

HAZOR JUDSON SMITH.
